ELECTRONIC DISCHARGE DEVICE

Charles Grover Smith, Medford, Mass., assignor,
by mesne assignments, to Raytheon Manufacturing Company, Newton, Mass., a corporation
of Delaware

Application February 16, 1926, Serial No. 88,558
Renewed August 3, 1929

20 Claims. (Cl. 250—27.5)

This invention relates to gaseous conduction space-discharge devices which contain an attenuated ionizable gas. Objects of the invention are to lower the voltage drop between anode and cathode, to increase the current or electronic discharge in tubes of this type and in general, and to produce a unidirectional gaseous conduction device operating with an arc-like discharge that has a voltage drop between cathode and anode below that required to maintain a glow discharge, no cathode dark space, low normal cathode voltage drop. Herein the term—arc-like discharge—and equivalent phrases mean, a discharge in which the cathode voltage drop is of the order of the ionization voltage of the gas in the device or less.

According to this invention the region surrounding a part or all of the active cathode surface is confined and the radiation and conduction of heat from this part is retarded so that the surface may be maintained at a high temperature by the discharge whereby the cathode operates at a temperature at which rectification is dependent on thermionic emission. For example the cathode may be hollow, with a restricted opening through which the anode is presented to its interior, and the thermionically active surface of the cathode may be in the form of a projection or plate extending from the cathode wall into the interior of the cathode and opposed thereto. In conjunction with this confinement of the active cathode surface the intervening gas space adjacent this surface preferably has a small dimension perpendicular to the surface so that the cathode end of the discharge is disposed between two relatively closely spaced surfaces, both at approximately the same potential, whereby the discharge is further facilitated and intensified. The length of the spacing or gap between the opposed surfaces should be of the order of that of the dark space which would exist in the absence of one of the surfaces. This spacing corresponds to the mean free path of the gas filling in the tube. By inclining the surfaces relatively to each other to partition off a narrow tapering cell from the interior space of said cathode, the space between said surfaces varies in width and the tube is more adaptable to different conditions of operation, the discharge extending farther into the tapered space upon increase of gas pressure and automatically shifting to the area affording most efficient operation in the event of change in pressure due to absorption or liberation of gas during operation.

55 In the accompanying diagrammatic drawing,

Fig. 1 is a central longitudinal section of one embodiment of the invention:

Fig. 2 is a similar view of another embodiment;

Fig. 3 is a section on line 3—3 of Fig. 2 and

Fig. 4 is an enlarged longitudinal central section of one of the anodes and associated parts.

The particular embodiment shown in Fig. 1 comprises a tube or envelope T, preferably formed of glass, a hollow cathode K of suitable conducting material such as iron or nickel, and anodes A and A' of tantalum, molybdenum, carbon or other suitable material. The cathode is formed in two parts, the upper part being in the form of an inverted cup with an exterior flange around its mouth and the lower part D being in the form of a disk secured to said flange as by welding and closing said cup. The disk has two spaced anode apertures or openings O and O' (Fig. 3) with depending flanges preferably being spaced from the anodes a distance less than or comparable to the mean free paths of ions or atoms in the gas. The anodes A and A' extend through the openings O and O' respectively into the cup. Each anode comprises a metallic tube B (Fig. 4) having a lead-in wire E extending therethrough, the two being pinched together at their upper ends to secure them together. Insulating sleeves F, of quartz lava or the like, surround the lead wire and substantially close the lower ends of the flanged openings, the re-entrant stem S of the tube having recesses to receive the sleeves. While the cathode may be supported on the sleeves F it is preferably supported independently of the anodes by lead G and wire H, although the sleeves F position the cathode relatively to the anodes so that the cathode openings are concentric with the anodes respectively. For many purposes, such a rectifying 110 volt 60 cycle current for the filament circuits of radio receiving sets, the tube may be filled with an inert monatomic gas such as helium at 17 mm. pressure and a small quantity of mercury vapor, caesium or other readily ionizable gas may also be incorporated in the tube. The gaseous atmosphere in the tube during operation has a substantial pressure sufficiently high to supply sufficient positive ions to the space discharge to neutralize the space charge of the electron current between the cathode and anodes to the desired extent and at which an arc-like discharge takes place between the anodes and the active surfaces within the cathode structure.

In accordance with this invention active cathode surfaces are provided upon the interior of the

thermionic cathode structure, preferably spaced close together. As shown in Fig. 1 these surfaces are provided by a series of rings R secured to the cathode and having their central openings aligned 5 to permit the discharge to pass between the respective rings and the anodes. Thus the upper portion of the cathode cup cooperating with the lowermost ring R forms a cathode enclosure. In this enclosure there is an opening in the lower- 10 most ring R for the passage of electrons from the cathode to the anodes A and A' and said anodes are spaced away from the cathode to permit ionization therebetween. The aligned central openings of the rings R provide a common dis- 15 charge space or crater into which the relatively narrow intercommunicating cells or spaces between the rings terminate or open. The inner surface of the cathode enclosure is at least twice the area of said opening in the lowermost ring 20 and thus the spaces between the rings are bordered by a relatively large surface area. Rings may be formed of material such as tungsten, which withstands extremely high temperatures, although under many conditions of operation they 25 may be made of nickel or even iron. The spacing between the rings may vary considerably but when operating at a pressure of the order of 17 mm. the spacing is preferably of the order of 2 mm. which is approximately the mean free 30 path of the gas. The rings may be caused to emit more efficiently if they are coated with a material of high electron emissivity such as an alkali metal or alkali earth metal or oxide of an alkali metal or alkali earth metal or if they have 35 metallic thorium incorporated therein. Preferably this coating material, which enhances the electron emissivity of the cathode, should be one which is substantially solid at the normal operating temperature of the tube envelope T. Materials 40 which are solid under these conditions will be termed herein—solid substances or materials. The hollow cathode may also be similarly constituted. Due to the above configuration the cathode structure as a unit when heated has a sub- 45 substantially smaller effective outer heat radiating area than electron-emitting area. Decrease of gas pressure due to absorption of the gas by the hot cathode surfaces is also substantially avoided by coating the surfaces as herein described, as- 50 sisted under some conditions by the presence of mercury vapor as described in my prior applica- 55 tion, Serial No. 55,262.

The modification of Figs. 2 and 3 is like the embodiment shown in Fig. 1 except in that the 55 plate constituting the active cathode surface, instead of being in ring form as in Fig. 1, is in the form of a ribbon which is anchored at one end to the inside of the cathode, is oppositely disposed thereto, and spirals inwardly therefrom. By vir- 60 tue of the spiral the dimension of the gas space adjacent the ribbon varies in thickness throughout the length of the ribbon. The area of the openings left between the convolution or ribbon R' and the walls of the cathode cup is less than 65 the internal area of said cup and said convolution.

In operation the discharge passes between the anodes and the interior of the hollow cathode structure which constitutes an enclosure confin- 70 ing a part of the space in the tube. The plate surfaces inside the cathode (rings R of Fig. 1 or spiral R' of Fig. 2) become highly heated to thermionic emission by the discharge owing to the fact that they are enclosed by the cathode 75 and are juxtaposed or spaced close together and

close to the wall of the enclosure; consequently these surfaces function as thermionic electron emitters with marked efficiency and most of the electronic discharge emanates therefrom rather than from the interior of the enclosure. Thus 5 the enclosure need not be formed as a part of the cathode. With the region around the hot cathode surfaces R or R' closely confined the excitation and ionization of the gas within the enclosure becomes sufficiently intense to produce 10 ions and electrons capable of carrying the discharge current. Thus I have discovered a unique method of producing an arc discharge by heating the cathode to a temperature at which the oxide coating has an effective electron emission to produce 15 thermionic emission from a closely confined area by heat from the discharge terminating at the area.

The oxide coating in the cathode is relatively non-volatilizable and remains substantially intact 20 at an effective electron-emitting temperature. Moreover, by virtue of the location of the oxide coating inside the hollow cathode with only a restricted opening therefrom, particles of the coating which may be dislodged by ion bombard- 25 ment are redeposited upon the inside of the cathode, little if any of the dislodged particles escaping through the restricted opening through which the spaces between the rings R communicate with the exterior. Thus the closely adjacent walls 30 of the rings, which are positioned in heat-shielding relation to one another, also provide deep contracted spaces whereby the oxide coating is conserved in the cathode enclosure at a tempera- 35 ture of thermionic emission. This not only con- 40 serves the coating but it avoids the deleterious effects which would result from the particles redepositing upon the inside wall of the glass container or vessel or upon other surfaces inside the container.

For many purposes improved operation is ob- 45 tained by forming the cathode coating at least in part of alkali metal or alkali earth metal instead of an oxide of the metal. Such a coating may be effected by first applying an oxide coating and then operating the tube on heavy current 50 while still on the vacuum pump, thereby reducing the oxide to metallic form by removing the oxygen. This reduction may be partial or complete 55 depending upon the intended use of the tube but for most purposes I prefer not to reduce the oxide completely. The reduction product appears to amalgamate with the cathode and forms a re- 60 markably durable and efficient emitting surface. 65

I claim:

1. A gaseous conduction device comprising an envelope containing an attenuated atmosphere, a hollow cathode, forming a cup, a disk closing the cup, spaced apertures extending through the disk, a plurality of anodes projecting through the apertures into the cup, and a thermionically active surface projecting from the cup interiorly thereof and opposed thereto, forming an intervening gas space between the said thermionically active sur- 70 face and the said cup interior, the width of said space being of the order of that of the dark space which would exist in the absence of one of said surfaces.

2. An electrical space discharge device com- 75 prising a vessel containing an anode, a cathode structure constituting an enclosure confining a part of the space in said vessel, said cathode structure having in the interior of the enclosure oppositely disposed tapering conducting wall 80

- members having juxtaposed electron emitting surfaces to be heated to thermionic emission during operation and partitioning off a narrow tapering cell from the interior space of said enclosure, 5 and an ionizable gas having during operation a pressure at which an arc-like discharge takes place between said anode and the interior of the tapering cell within the enclosure of said cathode.
3. An electrical discharge device comprising 10 the combination of an envelope, an attenuated gas filling at a pressure sufficiency high to neutralize space charge, a cathode therein operating at a temperature at which rectification is dependent upon thermionic emission, said 15 cathode comprising an enclosure of conducting material having a solid material of high electron emissivity in said enclosure, and an anode spaced away from said cathode to permit ionization therebetween, said cathode enclosure having an 20 opening for the passage of electrons to said anode and having closely adjacent walls providing a deep contracted space, whereby said electron emissive material is conserved in said enclosure at a temperature of thermionic emission, the inner 25 surface of the enclosure being at least twice the area of the opening leading therefrom.
4. An electrical discharge device comprising an envelope, electrodes therein, including a thermionic cathode having walls providing contracted 30 spaces communicating with the exterior, a material in said spaces which is capable of enhancing the electron emissivity of said cathode, said cathode being adapted to be heated during operation to a temperature at which said material has 35 an effective electron emission, and a gas in said envelope at a pressure which is sufficiently high to neutralize space charge during the operation of the device.
5. An electrode for an electrical discharge 40 device, said electrode having a plurality of adjacent wall members positioned in heat-shielding relation to one another and separated by deep contracted spaces which are open to the exterior, a material on each of said wall members which is 45 relatively non-volatilizable at an effective electron-emitting temperature within said spaces for enhancing the electrical emissivity of said electrode, said electrode being adapted to be heated to a temperature of thermionic emission during 50 operation.
6. An electrode for an electrical discharge device constituted of conducting material formed into a hollow body having a convolution within its confines, the area of the openings left between 55 said convolution and the walls of said hollow body being less than the internal area of said hollow body and said convolution, and a thermionically active material coating said electrode, said material being conserved at a temperature 60 of effective electron emission, said electrode being adapted to be heated to a temperature of thermionic emission during operation.
7. An electrical discharge device comprising co-operating electrodes, one of which is provided 65 with a cavity having an opening for the escape of electrons, and having a projection extending into said cavity, the surface of which is in communication with the exterior through said opening, and an activating material on said projection 70 which will be conserved in said cavity during the operation of said device, said activating material being adapted to be heated to temperature of thermionic emission during operation.
8. An electrical space discharge device comprising a vessel having therein an anode, a cath-

ode structure comprising conducting members surrounding a plurality of spaces bordered by a relatively large surface area having thereon an activating material adapted to be heated to thermionic electron emission during operation, 5 said cathode structure as a unit having, when heated, a substantially smaller effective heat-radiating area than electron-emitting area, and an ionizable gas in said vessel at substantial pressure at which sufficient positive ions are supplied 10 during operation to the space discharge to neutralize the space charge and secure low cathode voltage drop.

9. An electrical space discharge device comprising a vessel having therein an anode, a hollow cathode structure having an extended interior solid electron-emitting wall surface of substantially greater area than the outer heat-radiating surface of the cathode, said wall surface having thereon an activating material adapted to be 15 heated to thermionic electron emission during operation, said cathode structure having a discharge opening for passing a space discharge between the interior electron-emitting surfaces thereof and said anode, and an ionizable gas in 20 said vessel at substantial pressure at which sufficient positive ions are supplied during operation to the space discharge to neutralize the space charge and secure low cathode voltage drop.

10. An electrical space discharge device comprising 30 a vessel having therein an anode, a cathode structure comprising a hollow conducting member having in the interior a plurality of projections having thereon an activating material adapted to be heated to thermionic electron emission during operation, the surfaces of said projections constituting, in conjunction with the interior surfaces of said hollow member, an extended electron-emitting area larger than the heat-radiating area of said cathode, said cathode 40 having a discharge opening for passing a space discharge between the interior electron-emitting surfaces thereof and said anode, and an ionizable gas in said vessel at substantial pressure at which sufficient positive ions are supplied to the space 45 discharge during operation to neutralize the space charge and secure low cathode voltage drop.

11. An electrical space discharge device comprising a vessel containing an anode and a cathode structure having a plurality of conducting wall members with relatively extended juxtaposed electron-emitting surfaces bounding spaces therebetween designed to be heated to thermionic emission during operation, an activating material 50 on said surfaces during operation to enhance the electron emission thereof, an ionizable gas having during operation a pressure sufficient to sustain a discharge at low voltage drop between anode and cathode, said cathode structure also 55 comprising a hollow enclosure member surrounding said wall members for maintaining said electron-emitting surfaces at temperature of electron emission during operation of the device, the gas between said surfaces to be simultaneously maintained in sufficiently excited condition so that a discharge at low cathode voltage drop is secured between said cathode and anode.

12. An electrical space discharge device comprising a vessel containing an anode, a cathode 70 structure constituting an enclosure, said cathode structure having in the interior of the enclosure oppositely-disposed conducting wall members having juxtaposed electron-emitting surfaces adapted to be heated to thermionic emission dur-

- 5   16. A crater cathode for a discharge tube, comprising a plurality of parallel disks having aligned perforations forming the crater, said disks being spaced to provide a discharge region between them. 5
- 10   17. An electrical discharge device comprising a vessel containing a gas, co-operating electrodes, one of which is provided with a cavity, an opening for the escape of electrons, and having a projection extending into said cavity, the surface 10 of which is in communication with the exterior through said opening, and an activating material on said projection which will be conserved in said cavity during the operation of said device, said activating material being adapted to be heated 15 to temperature of thermionic emission during operation.
- 15   18. An electrical discharge device comprising a vessel containing a gas, mercury vapor, co-operating electrodes, one of which is provided with 20 a cavity, an opening for the escape of electrons, and having a projection extending into said cavity, the surface of which is in communication with the exterior through said opening, and an activating material on said projection which will 25 be conserved in said cavity during the operation of said device, said activating material being adapted to be heated to temperature of thermionic emission during operation.
- 20   19. An electrical discharge device comprising a 30 vessel containing a gas, a vapor, co-operating electrodes, one of which is provided with a cavity, an opening for the escape of electrons, and having a projection extending into said cavity, the surface of which is in communication with 35 the exterior through said opening, and an activating material on said projection which will be conserved in said cavity during the operation of said device, said activating material being adapted to be heated to temperature of thermionic 40 emission during operation.
- 25   20. An electrical discharge device comprising a vessel containing a gas, co-operating electrodes, one of which is provided with a cavity, an opening for the escape of electrons, and having a 45 projection extending into said cavity, the surface of which is in communication with the exterior through said opening, and an activating material on said projection which will be conserved in said cavity during the operation of 50 said device, said activating material being adapted to be heated to temperature of thermionic emission during operation, said gas having a pressure at which an arc-like discharge occurs.

CERTIFICATE OF CORRECTION.

Patent No. 2,201,818.

May 21, 1940.

CHARLES GROVER SMITH.

It is hereby certified that error appears in the printed specification of the above numbered patent requiring correction as follows: Page 1, first column, line 7, strike out the word "and"; and second column, line 39, for "a" read --as--; page 2, first column, line 21, for "Rings" read --The rings--; page 3, first column, line 11, claim 3, for "sufficiency" read --sufficiently--; line 23, same claim, for "missive" read --missive--; same page, second column, line 12-13, claim 8, for "cathods" read --cathode--; and that the said Letters Patent should be read with this correction therein that the same may conform to the record of the case in the Patent Office.

Signed and sealed this 2nd day of July, A. D. 1940.

(Seal)

Henry Van Arsdale,
Acting Commissioner of Patents.
